The ornamental design for a shovel, as shown and described.

DESCRIPTION

FIG. 1 is a perspective view of a shovel showing our new design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof;

FIG. 8 is another perspective view thereof, showing that the rod of the shovel is extended in a first use state; and,

FIG. 9 is another perspective view thereof, showing that the rod of the shovel is folded in a second use state.

The broken lines in the drawings illustrate portions of the shovel and form no part of the claimed design.
